UNITED STATES PATENT OFFICE.

JOHN LUKOWSKI, OF CHICAGO, ILLINOIS.

AUTOMOBILE EMERGENCY-WRENCH.

1,088,786.

Specification of Letters Patent.

Patented Mar. 3, 1914.

Application filed June 30, 1913. Serial No. 776,637.

To all whom it may concern:

Be it known that I, JOHN LUKOWSKI, a citizen of the United States, residing at Chicago, in the county of Cook and State of Illinois, have invented certain new and useful Improvements in Automobile Emergency-Wrenches; and I do hereby declare the following to be a full, clear, and exact description of the invention, such as will enable others skilled in the art to which it appertains to make and use the same.

This invention relates to new and useful improvements in wrenches, and as its principal object contemplates the provision of a device of this character which is particularly adapted for employment with automobiles.

A further object is to provide a wrench which consists essentially in a number of bar wrenches of various sizes formed with jaws of customary shape and designed in such manner that nuts and bolts of any size within a reasonable range may be effectively and conveniently manipulated by merely pulling out the desired bar wrench from the body casing which contains all of the bar wrenches.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 is a top plan view illustrating the various wrench bars in inoperative relation to each other and to the body casing. Fig. 2 is a side elevation. Fig. 3 is a section on the line 3-3 of Fig. 2. Fig. 4 is an end view illustrating one set of wrench jaws. Fig. 5 is a section on the line 5-5 of Fig. 2. Fig. 6 is a detail view of the slide plates employed in connection with the slideable shanks of the bar wrenches.

Proceeding now to the description of the drawings, the numerals 10 and 11 designate as an entirety the two sets of bar wrenches which are arranged with their shanks slidably mounted in a body portion which forms the handle of the wrench and is designated

in Fig. 1 as an entirety by the numeral 12. Each bar wrench is of the ordinary and usual type, as will be observed particularly by reference to Fig. 3 with the exception that the free terminal of each bar wrench shank is enlarged as at 13 to produce shoulders 14 and 15, which by engagement with similar shoulders 16 and 17 formed in the body portion 12, limit the outward movement of the wrench shank. In this connection it is to be observed that the body portion is bifurcated from each terminal toward a central partition or stop wall 18 which is concaved to conform to the rounded terminals of the shanks of the bar wrenches. As will be readily discerned by reference to Fig. 5, the wrench shanks are all formed with a longitudinally extending slot in each of which is mounted a leaf spring as at 19, this leaf spring is arranged to frictionally engage and to slide over spacing plates 20 which are formed of thin sheet steel or any desired metallic substance, and are interposed between the various wrench shanks. The conformation of these members 20 is similar to that of the wrench shanks in that they are provided with stop shoulders which by engagement with the shoulders 16 and 17 operate to limit their outward movement when the various wrench bars are withdrawn from the body casing when put into operation.

The bar wrench construction and design of the various springs and shoulders of the sets 10 and 11 are similar to the wrench jaws indicated at 21 and are made of various sizes, as particularly illustrated in Fig. 4. The purpose of the variation in size of the wrench jaws will be apparent, for it is a fact of common knowledge that when making hasty repairs, it is found necessary to remove and apply nuts and bolts of various dimensions. The shanks of the various bar wrenches are held in assembled relation in the body portion by a casing heretofore designated by the numeral 12. This casing is composed, respectively, of two sections, each section being substantially U-shaped in cross section and made of sheet brass, galvanized iron, or any other suitable economical and practical material. The two sections of the casing 12, to be hereinafter designated by the numerals 21 and 22, are secured to the body portion by means of screws 23, or other fastening devices, and are equipped at their terminals with cut-

wardly directed curved tongues or shoulders 24 which conform to the rounded edge 25 of the wrench jaws and continue the curved outline of the curved edges 26 of the terminals of the body portion.

The actual construction and arrangement of the various parts of the wrench of this invention being thus disclosed, it now remains to describe the manner in which the various bar wrenches are manipulated when it is desired to arrange them in operative position. Briefly the operation is as follows: The wrench which the operator desires to use is merely withdrawn from the body portion of the wrench or handle to bring it into operative position, indicated in dotted lines in Fig. 3. By reference to this figure, it will be noted that the wrench jaw is projected beyond the wrench jaws of the set and is in such position that it may be readily applied to any bolt or nut in the usual manner and that the body portion of the wrench forms a convenient handle for manipulating the wrench jaw. It is also to be observed that when the wrench jaws are in their operative and inoperative positions, the springs 19 act by frictional engagement with the plate 20 to hold the shanks of the wrench in the desired adjusted position.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus described my invention, what I claim is:

1. In a multiple bar wrench, a body member formed with longitudinally extending bifurcations extending inwardly from each end toward the center, a stop wall between the inner terminals of said bifurcations, a plurality of bar wrenches having their shanks mounted for sliding movement in said bifurcated portions of said body member, a casing for said body member and said wrench shanks, means for limiting the outward sliding movement of the said wrench shanks, and means for yieldingly holding said shanks in adjusted position.
2. In a multiple bar wrench, a body member having bifurcations directed inwardly from each terminal, a stop wall arranged centrally of the body portion, a plurality of bar wrenches having their shanks mounted

for sliding movement in said bifurcated portions, said stop wall being adapted for limiting the inward movement of said shanks, a casing for said body member, means for limiting the outward movement of said shanks, and means for holding the said shanks in adjusted position comprising a plurality of leaf springs carried by said shanks.

3. In a multiple bar wrench, a body member having a pair of longitudinally extending bifurcations directed inwardly from each terminal, a plurality of bars having their shanks mounted for sliding movement in said bifurcations, stop shoulders formed on the inner terminal of each shank, stop shoulders formed on the body member and adapted to engage the stop shoulders of the said shanks for limiting the outward movement of said shanks, means for limiting the inward movement of said shanks formed integrally with the body member, a leaf spring secured to each of said shanks, spacing plates arranged between said shanks, and a casing for said body member.

4. A multiple bar wrench, comprising a body portion formed with longitudinally extending bifurcations disposed inwardly from each end and toward the center, a stop wall between the inner terminals of said bifurcations, a plurality of bar wrenches having their shanks mounted for sliding movement in said bifurcated portions of the body portion, a casing for said body member and said wrench, means for limiting the outward sliding movement of said wrench shanks, and means for yieldingly holding said shanks in adjusted position carried by each of said shanks adjacent the inner terminal thereof.

5. In a multiple bar wrench, a body portion provided with longitudinally extending bifurcations extending inwardly from each end toward the center, a stop wall between the inner terminals of said bifurcations, a plurality of bar wrenches having their shanks mounted for sliding movement in said bifurcated portions of said body portion, means for limiting the outward sliding movement of said wrench shanks carried by the wrench shanks and body portion, means for yieldingly holding said shanks in adjusted position carried adjacent the inner terminal of each of said shanks and means mounted within the body portion and between each of said shanks for spacing said shanks.

In testimony whereof I affix my signature in presence of two witnesses.

JOHN LUKOWSKI.
